BLAST FURNACE BOTTOM AND METHOD OF
CONSTRUCTING SAMEFred M. Miller, Bala-Cynwyd, Pa., assignor to
General Refractories Company, Philadelphia,
Pa., a corporation of Pennsylvania

Application June 6, 1944, Serial No. 538,907

9 Claims. (Cl. 266—25)

1

The object of the invention is to provide improvements in the composition of blast furnace bottoms and the method of constructing same.

Another and more specific object is to provide in a blast furnace bottom a greater concentration or mass of refractory material within any given furnace dimensions, and to insure a more unitary resulting structure than has heretofore been possible.

Accepted practice heretofore has been to assemble in closest possible juxtaposition multiple courses or layers of accurately formed brick (usually 18" x 9" x 4 1/2"), each brick being carefully molded, handled and fired, so as to produce and preserve its desired dimensions and the accuracy of its corners and edges, even to the extent that they are frequently ground, in order to insure strictly planar surfaces and resulting intimate and uniform contact when assembled. However, with all of these precautions it is a practical impossibility to secure such a permanently tight fit and solidarity of the mass, that slight shrinkage therein will not cause joints to open up and metal to eventually escape.

In line with this effort to obtain exactness and superior workmanship in the manufacture of blast furnace bottom blocks, emphasis is stressed upon insuring these essential characteristics, with the result that firing temperatures have to be regulated to a point where the density of the fired blocks usually runs to a maximum of approximately 1.22 ounces per cubic inch, since higher firing temperatures tend to cause kiln marking and a prohibitive degree of distortion, making them unfit for assembly in accordance with present day practices.

A further object, therefore, is to provide a means or method whereby the mass or density of blast furnace bottoms may be economically increased, by permitting the practical manufacture of denser bricks or blocks, which can be assembled into a solid mass subject to reduced shrinkage in service, when and as subjected to furnace operating conditions. Thus, with exactness of workmanship no longer the chief criterion in judging bottom bricks or blocks, and the fact that they may be more economically produced to secure maximum density with a given raw material, followed by assembly or installation in accordance with the present invention, it is accordingly possible to increase the mass of blast furnace bottoms by as much as 9% to 10%. Likewise, since a furnace bottom of average size requires in the neighborhood of 1,250,000 pounds of refractories, it is readily appreciated that the present invention makes it possible to incorporate an additional 110,000 to 125,000 pounds within the same space, thereby imparting to the unit structure of refractory material greater vol-

ume stability and resulting longer life under given conditions.

Still another object, therefore, is to provide an improved method of assembly, whereby such high-fired and resultingly dense bottom blocks or brick, even though considerably distorted, may be incorporated into a matrix of specially prepared ramming mixes to form a solid mass of high overall density. While refractory ramming mixes are not new, and it is well known that if properly prepared a high degree of density can be attained, as by ramming with pneumatic tools, such refractory ramming mixes have not heretofore been employed to overcome the difficulties and problems which characterize blast furnace bottom construction. Also, instead of constructing a furnace bottom of bricks and refractory ramming mixes of the same materials throughout, they may be varied in accordance with their position or elevation in said bottom, and therefore with relation to the service to which they are subjected during operation of the furnace. For example, one or more of the first-laid lower courses might comprise intermediate heat duty brick separated by Lumnite or Portland cement, the next courses composed of high heat duty brick separated by an intervening ramming mix comprising predominantly calcined clay materials, the next course or courses being composed of high fired refractory bricks and intervening ramming mix consisting of high temperature-resisting materials such as sillimanite, magnesite, or the like, and the one or more uppermost courses comprising carbon blocks separated by a carbon base ramming mix.

The ramming mixes herein referred to comprise calcined materials in granular form, together with a small proportion of suitable bonding material, and of such analysis that they intimately adhere to the adjacent brick surfaces, and produce a resultingly homogeneous unitary bottom structure having such a high degree of cohesion as to resist the escape of molten metal therethrough, as sometimes occurs.

With the objects thus briefly stated, the invention comprises further details of construction, which are hereinafter fully brought out in the following description, when read in conjunction with the accompanying drawings, in which Fig. 1 is a vertical, diametrical section through the bosh and hearth or cupola sections of a representative type of blast furnace having a bottom of the improved construction; Fig. 2 is a fragmentary section approximately on the line 2—2 of Fig. 1, with successive courses of brick and intervening layers of ramming mix uncovered to varying degrees; Fig. 3 shows one method of assembling consecutive rows of brick in a given course, and the application of the ramming mix therebetween; Fig. 4 is an enlarged fragmentary portion

of a given course, showing a modified method of assembling bricks and intervening ramming mix; Fig. 5 is an extended section on the line 5—5 of Fig. 4; and Fig. 6 is a perspective view of a fragmentary portion of the matrix structure of the ramming mix per se, to show among other things the impenetrability of the improved bottom construction to molten metal.

Referring to Figs. 1, 2 and 3, the major part of the lower portion of a representative type of blast furnace is shown as comprising the customary circular bosh and hearth sections 1 and 2, respectively, superimposed upon a bottom 3, said bottom being usually of considerable downward extent through eight, ten or even more brick courses, supported in turn by still lower bodies of brick, concrete, or the like, but as neither the ultimate foundation nor the depth of the bottom enters into the invention, and the upper five or six brick courses alone will suffice to illustrate one embodiment of the invention, the full height of said bottom and its foundation are not shown.

Primarily the furnace bottom is constructed within a cylindrical metallic casing 4 and a concentric cast iron hearth jacket 5, spaced apart by intervening grouting material 6 of any suitable character, and surrounded by concrete (and/or brick) reinforcement 7, that also serves to support the usual plurality of circumferentially spaced column 8, which support the weight of the inwall and top sections of the furnace proper above the mantel 8a, as well as the bustle air and water ducts, ore-handling machinery and other super-structure associated therewith.

The said bosh and hearth sections comprise brick walls 1a and 2a, respectively, which are interspersed with water-cooled plates 9, while circumferentially spaced hot-air nozzles 10 extend through the upper portion of the hearth section to convey to the ore therein air that has been preheated by so-called stoves in well-known manner. The bosh section is probably always conical as to its inner surface, which merges flush into the corresponding surface of the cylindrical hearth section.

Said hearth section rests directly upon the bottom 3, which as shown is composed of any desired number of vertically arranged courses of brick 11. These brick are preferably of substantially the same size for uniformity, regularity of arrangement and easy handling, and are stood on end in each course but are angularly related in adjacent courses. Also, whereas it has heretofore been considered essential that broken joints be maintained between bricks in adjacent courses, in the present improved construction, broken joints, though maintained as far as possible following the usual practice, are not so essential, since adjacent courses are separated by interposed layers 12 of the ramming mix.

As will be seen from the drawings, which are drawn fairly closely to scale, adjacent bricks in the same course are spaced approximately two and one-half to three inches apart, or a sufficient distance to permit the ready insertion and operation between them of any well known form of air-driven ramming or tamping tool, while compressing the ramming mix in the vertically extending sections 13. By contrast, the thickness of the horizontal layers of the mix may be of any desired depth, either the same as, or more or less than, that between the bricks of the same course.

Referring to Fig. 3, there is here shown one method of assembling the bricks in the improved construction. An initial row of bricks is laid in

spaced relation with one another and preferably in alignment. Such row may be at the center of the hearth bottom coincident with a diameter, or may be adjacent to one side and coincident with a cord, as for instance the row of three brick 14. Between the adjacent wall surface and said bricks while backed by a short beam and between adjacent bricks in the same row ramming mix is compressed into place, it being noted that with the improved construction the bricks do not have to fit the surrounding hearth jacket closely, but instead may leave relatively large spaces 15 that are also filled with the mix alone, or with a combination of mix and broken or odd pieces of brick. A larger beam is then used to back up a second row of spaced bricks 16, after which the mix is rammed between the first row and the new row and between the bricks of said second row, as well as in the newly formed end spaces 15. This operation is

repeated until the point illustrated by Fig. 3 is reached, wherein a much longer beam 17 is employed to back up the thirteenth row of bricks 18, as they are laid in spaced relation with each other and with the last previous, or twelfth, row 19. The succession of beams of gradually increasing length, in one or more sections, is used in reverse order as the operation progresses through the second half.

The varying lengths of consecutive beams may be secured in fixed position by any suitable means, which merely for purposes of illustration is shown in Fig. 3 as comprising a plurality of blocks 20, which spread the force exerted upon them by jack bars 21 to spaced regions of the said beam. Each of said bars is adjustably positioned in any suitable manner, as for instance, by means of jacks 22, backed or shored by any available timber or the like, such as the central shoring blocks 23 and the single or built-up blocks 24, having diagonal or curved surfaces 25 for engagement with laterally spaced portions of the jacket 5, said central and lateral blocks being maintained in spaced relation by compression beams 26, or otherwise as may be desired. Finally, after all of the bricks of a given course have been laid by this method, a layer 12 of the mix is tamped over and across the entire area like a blanket, following which another course of brick is superimposed thereon but preferably arranged at right angles (or at least angularly) with respect to the bricks of the last completed course. This process is repeated until the desired depth or thickness of the furnace bottom is attained, whereupon the cylindrical hearth wall 2a is laid thereon in the usual manner, as shown in Fig. 1.

Referring to Figs. 4 and 5, a modified method of laying the brick in a given course is shown. By this method all of the brick 27 of a given course 28 are laid in preferably (though not necessarily) uniformly spaced upright position upon a layer of mix 12 immediately therebelow. Between the lowermost portions of said brick, both in longitudinal and transverse directions, are inserted spacing blocks or spacers 30 of any suitable non-compressible material, such as metal, plastic, ceramic, or otherwise. Upon the opposite sides of said blocks and between said bricks ramming mix 31 is inserted and rammed or tamped into place by any suitable tool 31a, whereupon said blocks are lifted and the spaces left vacant by their removal filled with the mix duly set by ramming. The blocks are then again inserted between said bricks in the elevated positions 32, and more of the mix 33 forced into position between them, and the blocks again lifted, their

vacated spaces filled with mix as before, and the blocks repositioned at their third level 34. After ramming additional mix between them, and then into the spaces from which they are finally lifted, the level of the mix is brought to the level of the upper surfaces 35 of said brick, as indicated at 36, and another blanket-like layer 12 of the mix added thereto and likewise rammed until the final hearth lining 37 is laid and rammed in place to finish the bottom. Obviously, however, only one or possibly two elevations of the spacers may be used, if preferred, instead of the three here described.

Fig. 6 has been included in order to show the characteristics of the ramming mix per se after being rammed in a complete bottom, that is, as though the mix were formed in the absence of the bricks, or the bricks removed from this fragmentary portion of the composite bottom structure, thereby clearly indicating the relationship of the numerous walls that cooperate to form the monolithic cellular or matrix structure, by which any molten metal that may enter between a slightly shrunken brick and the adjacent mix is trapped by the next lower horizontal layer of such structure, and thereby prevented from continuing further through and escaping from the furnace bottom as a unitary whole.

What I claim and desire to protect by Letters Patent of the United States is:

1. A furnace bottom, comprising a course of spaced intermediate heat duty brick, a hydraulic cement mixture rammed between them, a layer of mix upon said course, a second course of spaced high heat duty brick upon said layer of mix, a mix of granular calcined clay materials rammed between the bricks of said second course, a layer of mix upon said second course, a course of spaced high refractory brick upon said second layer, a mix rammed between the bricks of said last-mentioned course, and composed of high temperature-resisting materials selected from the group consisting of sillimanite and magnesite, a layer of the same mix material upon said last-mentioned course, a layer of spaced carbon brick upon said last-mentioned mix layer, and a carbon-base mix rammed between said carbon bricks.

2. A furnace bottom, comprising the combination of a course of intermediate heat duty brick, a course of high heat duty brick, a course of high refractory brick, a course of carbon brick, and a layer of rammed mix between two adjacent courses.

3. A furnace bottom, comprising the combination of superimposed courses of refractory brick, the joints between the bricks of each course being filled with a mix composed of materials selected from the group consisting of sillimanite and magnesite, and a layer of rammed mix between two of the adjacent courses.

4. A furnace bottom, comprising a course of spaced relatively low heat duty brick, a rammed hydraulic cement mix between the bricks of said course, a layer of a mix covering said course, a second course of spaced high heat duty brick upon said layer of mix, a rammed mix of granular calcined clay materials between the bricks of said second course, a layer of a mix covering said second course, a third course of spaced high-fired refractory brick upon said last-mentioned layer, a rammed mix of high temperature-resisting materials selected from the group consisting of sillimanite and magnesia-containing material between the bricks of said third course, a rammed layer of the same material covering said third

course, a fourth course of spaced carbon brick upon said last-mentioned layer, and a rammed mix having a carbon base extending across said fourth course.

5. A furnace construction, comprising superimposed courses of refractory brick, said courses and the bricks of each course being initially spaced apart, and a ramming mix composed principally of the same material as that which principally constitutes the material of said brick rammed into the spaces between adjacent courses and between the bricks of each course, said ramming mix uniting as an integral unit of itself and with the material of said brick to form a dense, monolithic mass of substantially uniform integral mixture.

6. A monolithic furnace bottom, comprising superimposed courses of refractory brick having substantially the same refractory characteristics, said courses and the bricks of each course being initially spaced apart, and a mix composed of material having at least as high refractory characteristics as that which constitutes the material of said brick rammed into the spaces between adjacent courses and between the bricks of each course, said mix coalescing with said bricks to form a substantially integral monolithic structure of substantially uniform density throughout said bricks and the intervening mix.

7. The method of constructing a furnace bottom, which consists in laying a course of spaced bricks, ramming between them a mix having substantially the same refractory characteristics as that of said bricks to attain a density of substantially the same order as that of said bricks, ramming a layer of similar mix upon said first course, in coalescing engagement with said first mix, laying a second course of spaced bricks upon said rammed layer, and ramming between the brick of the second course a similar mix in coalescing engagement with the mix of said layer, to form an integral monolithic structure of brick and mix having substantially uniform density throughout.

8. A monolithic furnace bottom, comprising superimposed courses of refractory brick, the brick of the uppermost course being of higher refractory characteristics than those of the lowermost course, said courses and the bricks of each course being initially spaced apart, and a mix composed of material having at least as high refractory characteristics as that which constitutes the material of the brick of said uppermost course rammed into the spaces between adjacent courses and between the bricks of said uppermost course, said mix coalescing with said bricks to form a substantially integral monolithic structure in which the bricks of the uppermost course and the rammed mix are characterized by substantially the same density.

9. The method of constructing a furnace bottom of a plurality of brick courses, which consists in laying a course of spaced brick, ramming between said bricks a mix, and upon them a layer of mix in coalescing engagement with the first mix, laying a second course of spaced bricks upon said rammed layer, and a mix between and in a layer upon said last-mentioned bricks, the bricks of the uppermost course being of higher refractory characteristics than those of the lowermost course, and the mix when rammed being of substantially the same density and at least as high refractory characteristics as that of the adjacent bricks.
